(57) **CLAIM**

The ornamental design for a portable test instrument, as
shown and described.

DESCRIPTION

FIG. 1 is a top front perspective view of a portable test
instrument showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The portions shown in broken lines, represented as dashed
lines, depict environmental structure only and do not form
part of the claimed design.

The broken lines represented as dot-dash lines, crossing the
article in all views, depict break lines which form no part of
the claimed design. The appearance of any portion of the
article between the dot-dash lines forms no part of the
claimed design.
